UNITED STATES PATENT OFFICE.

ANDREW ANGELL, OF REDWOOD FALLS, MINNESOTA.

SHIRT AND COLLAR FASTENER.

Application filed October 3, 1923. Serial No. 666,288.

To all whom it may concern:

Be it known that I, ANDREW ANGELL, a citizen of the United States, residing at Redwood Falls, in the county of Redwood 5 and State of Minnesota, have invented certain new and useful Improvements in Shirt and Collar Fasteners, of which the following is a specification.

My invention relates to means for fastening loose collars to shirts, and the main object is to so improve said means that they will not get accidentally separated from the parts they are to attach together but will always be found in place ready for use, and 10 are of such form and materials that they can not get broken by passing the parts through a clothes wringer.

In the accompanying drawing—

Fig. 1 is a front elevation of the upper 20 portion of a shirt and a collar attached together by my invention. Fig. 2 is an enlarged section on the line 2—2 in Fig. 1. Fig. 3 is a section on line 3—3 in Fig. 1. Fig. 4 is a section through the portion of the 25 collar band of the shirt holding the front collar button with the button therein. Fig. 5 is Fig. 4 modified. Fig. 6 is an enlarged partly sectional view of the collar button and the adjacent cloth, the button being 30 shown as built up of several parts of certain materials. Fig. 7 is a face view of a blank from which the spider 38 in Fig. 6 is formed. Fig. 8 is a rear view of the collar band. Fig. 9 is a top view of Fig. 4. Fig. 10 is 35 Fig. 9 modified. Fig. 11 is a front face view of the rear portion of the detachable shirt collar. Fig. 12 is Fig. 11 modified.

Referring to the drawing by reference 40 numerals, 15 designates the upper portion of a shirt having a collar band 16 upon which a collar 17 is detachably secured by means comprising a horizontal tongue 18 made of stiff canvas, or other suitable cloth reinforced by an inlaid strip 19 of whalebone, aluminum or other stiffening material. 45 One end of the tongue is secured by stitches 20 either directly to the collar band as in Fig. 11; or after being inserted between the folds 21 and 22 of the band, through a slit 23, as in Fig. 12. The free end portion of the tongue is designed to be pushed through an aperture 24 in the rear fold 16^a of the collar band 16 (see Fig. 8 and Fig. 2) and remain between the folds 16^a and 16^b as 50 long as the collar is to stay on the shirt.

In removing the collar the tongue 18 is

simply pulled out of the aperture 24. The latter is somewhat larger than just necessary, to make the insertion, adjustment and removal easy. The collar band is usually 60 double, and if it be a single thickness a piece of cloth (not shown) is sewed onto the collar band to form a pocket for the tongue to lie in. One front end of the collar band is provided with a button-hole 25 (shown 65 in Fig. 3) for a collar button 26 adapted to extend through said hole and also through button holes 27 and 28 in the front ends of the collar 17 to hold the latter and also the strap 29 of a necktie (not shown). 70

The collar button is made of material flexible enough to allow the button stem 26^a to bend, as shown in dotted lines in Fig. 4, when the shirt is passing through a clothes-wringer. The button may be made of suitably soft rubber or any other material that will stand bending without breaking. 75

In Figs. 3, 4, 5 and 9 the button may be considered as made in one single piece including its head, stem and a base plate 26^b, and the latter secured in or to the end of the collar band by stitches 30 and a cloth patch 31, as shown in Figs. 4 and 9; but the base 26^b may also be sewed in between the folds 80 of the collar band as shown in Fig. 5. 85

In Fig. 6 the button is built up of a piece of stiff braided cord forming its stem 26^a, and the base of the stem consists of the end of the cord spread as 32 between the folds 90 of the collar band and secured by stitches 30 in Fig. 6, or such stitches and a pad 33 (in Fig. 10). In this form the head of the button is a piece of rubber, or leather, 34, having a hole for the stem and a cavity 35 for a bud or knob 36 formed at the end of the stem or cord 26^a. The leather is then covered with a piece of canvas 37, the edge of which is gathered close around the stem and secured by a metal ring or spider 38 having several sharp prongs 39 at right angles to the body of the spider and pressed through the canvas and driven into the leather 35. Said spider and its legs or prongs are formed of a sheet metal blank 100 similar to that shown in Fig. 7. 105

The invention is applicable to both soft and starched shirts and collars of any desired softness or stiffness, and may be modified in many ways, one of which being that it is optional to have the tongue 18 secured on the collar and the aperture 24 in the collar band, or the tongue on the shirt and the 110

aperture in the collar. Such modification I consider as a mechanical equivalent in need of no further drawing, and it will be covered by the generic terms of the last one of the 5 following claim.

What I claim is:

A collar button having a resilient stem made of braided cord, a resilient head fixed on the outward end of said stem and a resilient base fixed at the inward end of the 10 stem and adapted to be secured to the collar

band of a shirt; said head comprising a body made of leather or similar material, a piece of canvas covering the head thus formed and having its edges gathered about 15 the stem close below the head, and a metallic spider having a central aperture for the stem and sharp prongs driven through the canvas into the leather.

In testimony whereof I affix my signature.

ANDREW ANGELL.
